UNITED STATES PATENT OFFICE

1,996,265

COKE OVEN MACHINE

Charles E. Underwood, Bethlehem, Pa., assignor
to Bethlehem Steel Company, a corporation of
Pennsylvania

Original application April 2, 1932, Serial No.
602,662. Divided and this application March
16, 1934, Serial No. 715,832

16 Claims. (Cl. 214—23)

My invention relates to the general arrangement of a machine for use in connection with retort by-product coke ovens and more especially to the manner of mounting the mechanism on a single carriage for removing and replacing the doors on the pusher side of the oven, ejecting the coke from the ovens, sealing the space around the doors after replacement and then leveling the coal after it has been charged into the oven, and is a division of my copending application, Serial No. 602,662, filed April 2, 1932.

The present machines of this type in use at the coke oven plants of today are equipped with tools for performing the following operations.

15 A door manipulating mechanism for removing and replacing the doors on the pusher side of the ovens.

A ram to push the coke out of the oven into the receiving car on the coke side of the ovens.

20 A leveling bar to level off the coal charged into the oven through an opening usually in the top portion of the door or above the same.

A mud buggy is also sometimes installed on the carriages of the machine which is used for sealing the space around the door after the coke has been ejected from the oven and the door replaced and before the oven is recharged with coal.

While thought and time has been expended to 30 improve the mechanical operation and durability of this equipment, its operations, on account of the different tools being mounted in fixed spaced relation to each other, usually take place one at a time, with the result that while the men working with this machine could easily do more work, their output is limited by the speed of operation of the machine. This lost time consumed by the carriage in traveling or moving back and forth to place itself in position to use its various tools 35 as needed to complete the cycle of operation.

From time to time bituminous coal is charged into one or more of the ovens of the battery while similar charges in other ovens are being coked. As the charges in various ovens forming 45 a battery or a number of batteries are in different conditions; some of the coal being green, other ovens filled with coal that is partially coked, still others with coke that is practically finished, this gives a fairly constant amount of distillate gas supply which is gathered in a collecting main from which point it is delivered to by-product recovering devices which separate the by-product from the gases, and a portion of the gas is then finally returned to the battery for heating 50 55

the same, while the excess gas is used for commercial purposes.

The finished charges of coke in the ovens are pushed in a coke plant in series of every fifth oven, tenth or some other combination that satisfies the management that the heat distribution through the battery of ovens is the best they can possibly obtain.

My machine is designed in such a manner that it can be built to meet the conditions of any particular plant. For illustration the one shown in the drawings covers the construction for a five oven series but it will be readily understood that by varying the distance between the leveling bar and door manipulator and pusher ram any pushing series may be obtained.

With my machine it is possible for the carriage to remain stationary while it completes four operations after ejecting the coke from the first oven.

One of the objects of my invention is to mount 20 horizontally side by side on a single carriage a combination of means which will make it possible to maintain the carriage in one position in front of the battery at the same time allowing the pusher ram and door manipulator to be 25 laterally adjusted in relation to the leveling bar.

Another object of my invention relates to the manner of mounting the door manipulator, pusher ram and leveling bar in spaced relation in such a manner that two ovens can be operated on at 30 the same time.

Another object of my invention relates to the particular manner of mounting and operating the leveling bar by gearing in such a way that the bar may be advanced or retracted by one 35 mechanism with separate mechanism for giving the leveling bar a comparatively short reciprocating stroke.

Other objects will appear hereinafter.

Having given a general description of my invention I will now, in order to make the same 40 more clear, refer to the accompanying two sheets of drawings in which like characters refer to like parts:

Figure 1 is a top plan of my improved machine 45 for handling the doors of coke ovens, ejecting the coke therefrom, leveling the charge therein and a mud box for sealing the doors, with a portion of the battery shown in section;

Fig. 2 is a side elevation of the machine shown 50 in Fig. 1; and

Fig. 3 is a side elevation of the leveling bar mechanism taken on the line 3—3 of Fig. 1.

In the drawings which are shown more or less diagrammatically, the numeral 1 indicates the 55

carriage provided with rollers 2 journaled in bearings mounted on the girders 3 and adapted to travel on the rails 4.

The axle 5 of two of the rollers 2 have gears 6 mounted thereon meshing with pinions 7 on the ends of a drive shaft 8, having a gear 9 mounted centrally thereon for meshing with a pinion 10 on the shaft of a motor 11 for rotating the shaft for operating the carriage.

Secured on top of the carriage near the rear end at one side thereof is a center bearing plate 12 having a central perforation adapted to receive the king bolt 13 extending from a bearing plate 14 secured to the under side of the pivoted platform 15 near the inner end, the forward and intermediate portion of the platform being supported on track segments 16 and 17 by means of rollers 18 which are secured to the platform by means of brackets, the forward end of the pivoted platform being limited in its lateral movement by means of stops 19. Standards 20, 21, and 22 are mounted at spaced intervals on the platform in which are mounted idler rollers 23 for guiding a pusher ram 24 which has a rack formed on its under side for meshing with a pinion 25 on shaft 26 journaled in the bearing 22, the outer end of said shaft being connected by means of reduction gearing 27, driven by means of a motor 28. Mounted in the platform 15 laterally thereof at one side of the pusher ram 24, is a door manipulator 29, mounted in standards 30 and 31 between idler rollers 32 for guiding the same. The under side of the shaft of said door manipulator having a rack formed thereon as at 33 meshing with a pinion 34, the shaft of which is journaled in standard 31 and connected with reduction gearing 35 and actuated by means of a motor 36. The forward end of the door manipulator being formed with hooks 37 for engaging the lugs 38 on doors 39 for closing the pusher side of the coke ovens 40. In order to adjust or swing the outer end of the platform 15 with the pusher ram 24 and the door manipulator 29 mounted therein, a motor 41 is mounted on the front end of the platform which is connected by means of gearing 42 to a rack 43 formed on the track segment 17.

A leveling bar 44 is mounted laterally of the pivoted platform on one side of the carriage 1, the forward end of the leveling bar being supported between standards 45 and idler rollers 46 while the rear end of the leveling bar is guided between posts 47 and idler rollers 48, mounted on a car 49 supported on wheels 50 engaging a track 51, said car having a motor 52 and reduction gearing 53 for bodily advancing the car and the leveling bar. The motor 52 and gearing 53 connected therewith will advance the leveling bar slowly into the coke oven. When the leveling bar encounters a pile of coal which cannot be leveled by the slow movement of the leveling bar into the oven the leveling bar can be given a short stroke reciprocating motion independent of the motor 52 by throwing in the motor 54 geared to crank arms 55 and pitmen 56 pivoted to a sector gear 57 journaled on the car body. This sector gear 57 engaging gears 58 and has a gear 59 adapted to engage a rack 60 on the under side of the leveling bar.

A mud buggy or bucket 61 is pivoted by means of an arm 62 to a standard 63 which may be swung out when desired for sealing the doors after they have been replaced before charging the ovens. An operator's cab 64 is mounted on the carriage in which the controllers (not shown)

for operating the different motors may be installed.

The operation of my invention is as follows: After the door of the first oven is removed by means of the door manipulator 29 and the platform 15 swung from the dotted position into the full line position indicated in Fig. 1 of the drawings the pusher ram 24 is then advanced into the oven the full length thereby ejecting the coke from the oven into a coke quenching car or the like receptacle on the opposite side of the battery, the pusher ram 24 is then returned to the position shown in the drawings and the platform swung into the dotted line position and the door replaced in the end of the oven, the carriage will then be advanced a distance equal to five ovens until the leveling bar is properly centered for its operation, the luter man will then swing out his luter box, and start his operation of sealing the door, while he is swinging out his luter box and completing his operation the movable platform 15 holding the pusher ram 24 and door manipulator 29 will swing into position, remove the door of the oven and swing the pusher ram into operating position. The operation of mudding the previous door taken off, taking off the door of the next oven to be pushed and swinging the pusher ram into position for its work will be finished at the same time. The first oven discharged having been recharged with coal in the usual manner the control is then thrown in, starting the leveling bar into operation, this can be then left to itself while the operator pushes the coke from the oven, after the coke in the oven has been ejected and the pusher ram retracted into its normal position, the door manipulating machine is operated to replace the oven door, the leveling operation has been completed and the carriage with the machines mounted thereon moves up another series of five ovens to repeat the cycle.

Although I have described and illustrated my invention in considerable detail, I do not wish to be limited to the exact and specific details thereof, as shown and described, but may use such modifications in, substitutions for, or equivalents thereof, as are embraced within the scope of my invention, or as pointed out in the claims.

Having thus described my invention what I claim as new and desire to secure by Letters Patent is:

1. In a machine of the character described, a carriage mounted to travel on a track, a leveling bar mounted on the carriage, stationary means for guiding and supporting the front end of the leveling bar, a movable car mounted on the carriage for guiding and supporting the rear end of the leveling bar having means mounted thereon for simultaneously advancing and retracting therewith the leveling bar and means mounted on the movable car and actuated independently of the movement of the car for imparting a plurality of short reciprocating strokes to the leveling bar.

2. In a machine of the character described, a carriage mounted to travel on a track, means for driving the carriage, a leveling bar mounted on the carriage, stationary means for guiding and supporting the front end of the leveling bar, movable means for guiding and supporting the rear end of the leveling bar having means mounted thereon for simultaneously advancing and retracting therewith the leveling bar, and independent means for reciprocating the leveling bar.

3. In a machine of the character described, a

carriage mounted to travel on a track, means for driving the carriage, a leveling bar mounted on the carriage, stationary means for guiding and supporting the front end of the leveling bar, a car having means mounted thereon for guiding and supporting the rear end of the leveling bar, means for simultaneously advancing and retracting the car with the leveling bar, and independent means for reciprocating the leveling bar.

4. In a machine of the character described, a carriage mounted to travel on a track, means for driving the carriage, a leveling bar mounted on the carriage having a rack formed thereon, stationary means for guiding and supporting the front end of the leveling bar, a car having means mounted thereon for guiding and supporting the rear end of the leveling bar, a motor mounted on the car having a reduction gear connection with a track for simultaneously advancing and retracting the car with the leveling bar, a motor mounted on the car having gearing for rotating a crank shaft, a pair of cranks mounted on the crank shaft, a pitman connecting each of the cranks with a pair of sector gears, gears mounted on a shaft meshing with the sector gears, and a gear mounted on the shaft between the pair of gears engaging the sector gears for meshing with the rack on the leveling bar.

5. In a machine of the character described, a carriage mounted to travel on a track, means for driving the carriage, a leveling bar mounted on the carriage having a rack formed thereon, means rigidly secured to the carriage for guiding and supporting the front end of the leveling bar, a movable car on the carriage having means mounted thereon for guiding and supporting the rear end of the leveling bar, a motor mounted on the car having a reduction gear connection with a track for simultaneously advancing and retracting the car with the leveling bar, and a motor mounted on the car and geared to the rack of the leveling bar adapted to reciprocate the leveling bar independent of the movement of the car.

6. In a machine of the character described, a carriage mounted to travel on a track, means for driving the carriage, a leveling bar mounted on the carriage having a rack formed thereon, means rigidly secured to the carriage for guiding and supporting the front end of the leveling bar, a car mounted on the carriage for guiding and supporting the rear end of the leveling bar, means for moving the car independent of the carriage, and means for engaging the rack for reciprocating the leveling bar independent of the car.

7. In a machine of the character described, a carriage mounted to travel on a track, means for driving the carriage, a leveling bar mounted on the carriage, means rigidly secured to the carriage for guiding and supporting the front end of the leveling bar, a car mounted on the carriage for guiding and supporting the rear end of the leveling bar, means for simultaneously advancing and retracting the car with the leveling bar, and means independent of the movement of the car for reciprocating the leveling bar.

8. In a machine of the character described, a carriage mounted to travel on a track, means for driving the carriage, a leveling bar mounted on the carriage having a rack formed thereon, stationary means for guiding and supporting the front end of the leveling bar, a car mounted on the carriage for guiding and supporting the rear end of the leveling bar, a motor mounted on the car having a reduction gear connection with a track for simultaneously advancing and retract-

ing the car with the leveling bar, and a motor mounted on the car having a gear connection with the rack of the leveling bar for reciprocating the leveling bar independent of the movement of the car.

9. The combination with a battery of coke ovens having a plurality of horizontal coke ovens with doors therefor, a carriage horizontally movable longitudinally of the battery and transversely of the ovens, a leveling bar, stationary means mounted on the carriage for guiding and supporting the front end of the leveling bar, a movable car mounted on the carriage for guiding and supporting the rear end of the leveling bar, means mounted on the car for advancing or retracting the leveling bar in the coke ovens, and means for reciprocating the leveling bar in the coke ovens independent of the movement of the car.

10. In a machine of the character described, a carriage mounted to travel on a track, means for driving the carriage, a leveling bar mounted on the carriage, means for guiding and supporting the leveling bar, a car mounted on the carriage for advancing and retracting the leveling bar transversely to the line of travel of the carriage, and means for imparting a short reciprocating stroke to the leveling bar independent of the movement of the car.

11. In a machine of the character described, a carriage mounted to travel on a track, means for driving the carriage, a leveling bar mounted on the carriage, a car mounted on the carriage for guiding and supporting the leveling bar, means for simultaneously advancing and retracting the car with the leveling bar transversely to the movement of the carriage, and means geared to the leveling bar for imparting a short reciprocating stroke to the leveling bar independent of the movement of the car.

12. The combination with a battery of coke ovens with doors therefor, a carriage horizontally movable longitudinally of the battery and transversely of the ovens, means rigidly secured to the carriage for guiding and supporting the front end of the leveling bar, a movable car mounted on the carriage for guiding and supporting the rear end of the leveling bar, means for driving the car for advancing and retracting the leveling bar in the coke ovens, and means mounted on the car for imparting a short reciprocating stroke to the leveling bar independent of the movement of the car.

13. In a machine of the character described, a carriage mounted to travel on a track, means for driving the carriage, a leveling bar mounted on the carriage having a rack formed thereon, means mounted in fixed relation to the carriage for guiding and supporting the front end of the leveling bar, a car mounted on the carriage and movable in relation thereto for guiding and supporting the rear end of the leveling bar, a motor mounted on the car having a reduction gear connection with a track for simultaneously advancing and retracting the car with the leveling bar, a motor mounted on the car connected with worm gearing for rotating a crank shaft, a pair of cranks mounted on the crank shaft, a pitman connecting each of the cranks with a pair of sector gears, gears mounted on a shaft journaled in the car structure for meshing with the sector gears, and a gear mounted on said shaft between the pair of gears engaging the sector gears for meshing with the rack on the leveling bar.

14. In a machine of the character described, a carriage mounted to travel on a track, means

- for driving the carriage, a leveling bar mounted on the carriage, means rigidly secured to the carriage for guiding and supporting the front end of the leveling bar, a car mounted on the carriage 5 movable transversely to the line of travel of the carriage for guiding and supporting the rear end of the leveling bar, means mounted on the car for simultaneously advancing and retracting therewith the leveling bar, and means mounted on the car for reciprocating the leveling bar independent of the movement of the car.
15. In a machine of the character described, a carriage mounted to travel on a track, means for driving the carriage, a car mounted on the carriage for guiding and supporting the leveling bar having means mounted thereon for simultaneously advancing and retracting the leveling bar
- therewith, and means mounted on the car for imparting a short reciprocating stroke to the leveling bar independent of the movement of the car.
16. In a machine of the character described, a carriage mounted to travel on a track, means for driving the carriage, a car mounted on the carriage for guiding and supporting the leveling bar, a motor on the car having a reduction gear connection with a track on the carriage for simultaneously advancing and retracting the leveling bar therewith transversely to the line of travel of the carriage, and a motor mounted on the car provided with a connection geared to the leveling bar for imparting a short reciprocating stroke to the leveling bar independent of the movement of the car.

CHARLES E. UNDERWOOD.
